UNITED STATES PATENT OFFICE.

JOHN B. KELLY, OF ANNISTON, ALABAMA, ASSIGNOR OF ONE-HALF TO JOSEPH SAKS, OF ANNISTON, ALABAMA.

HOLDING AND OPERATING MEANS.

1,089,226.

Specification of Letters Patent.

Patented Mar. 3, 1914.

Application filed April 5, 1913. Serial No. 759,123.

To all whom it may concern:

Be it known that I, JOHN B. KELLY, a citizen of the United States, residing at Anniston, in the county of Calhoun and 5 State of Alabama, have invented certain new and useful Improvements in Holding and Operating Means, of which the following is a specification.

My invention relates to means for operating and holding a receptacle, such as ice cream freezers, and it has for its objects among others to provide a simplified and cheap, yet durable and efficient device for this purpose and also one which will perform its functions in a rapid and easy manner without tiring or fatiguing the operator.

With these objects in view, my invention consists of a combined churn and freezer 20 embodying novel features of construction and combination of parts for service, substantially as shown, described and pointed out in the claim.

In order that the detailed construction 25 and the operation of my invention may be fully understood and its advantages and features of merit be fully appreciated, I have illustrated in the accompanying drawing a combined churn and freezer, constructed according to my invention.

Figure 1 represents a view in side elevation of a combined churn and freezer embodying my invention. Fig. 2 represents a 35 front elevation of the complete machine, and Fig. 3 represents a detail view of the novel clamp for holding the freezer in proper position.

Referring by numerals to the drawings, in which similar characters of reference are 40 used to denote corresponding parts in the several views: The numeral 1 designates the table or platform, supported upon legs 2, suitably braced by cross-pieces 3, and 45 forming the support or frame of my machine, which frame is of the proper dimensions to suit the requirements. Upon the platform is supported and secured by fastenings 4, the bed plate 5 from which rises the pair of vertical parallel supports or 50 standards 6, and to one side of one of the standards is secured the upper casting 7 and the lower casting 7', formed with sockets 8, in which fit the tubular guide-posts 9, upon which move the tubular sleeves 10 of the 55 traveling cross-head 11, which cross-head

carries the loop or eye 12, engaging the dasher rod 13, of the churn 14, and the dasher rod is securely retained in proper place in the traveling cross-head by means of a threaded stem or shank 15, passing 60 through the cross-head and engaged by the winged nut 16, which serves to bind the rod of the dasher and retain said rod in any adjustment in the cross-head.

From this construction it will be observed 65 that the churn is disposed at one side of the frame and is connected with the traveling cross-head, and to impart reciprocation to the cross-head and the dasher rod, I provide the pitman 17, having connection 18, 70 with the head and having its upper end 19 adapted to be connected to any one of the openings 20 upon the spokes 21, of the fly-wheel 22. This fly wheel 22 is formed on one side with a counterbalance 22', and is 75 secured upon the shaft 23, mounted in collars 24 forming bearings on the pair of standards, and this shaft carries a small gear wheel 25, meshing with a larger gear wheel 26, on the operating shaft 27, which 80 shaft is mounted in collars on the pair of standards forming bearings 28, and this shaft is extended at 29 and carries a hand crank 30, for revolving the shaft, and through its gearing revolving the fly-wheel 85 which through the pitman connection reciprocates the cross-head which moves the churn dasher and performs the operation of churning, as will be readily understood.

The operating shaft has secured thereto 90 adjacent the crank, the hub 31 which is formed with the sprocket wheel, 32, over which and the grooved smaller sprocket 33, on the freezer shaft passes the sprocket 95 chain 33', which serves to rotate the freezer shaft and effect the operation of freezing, and to retain the bucket 34 of the freezer in place, I employ the curved clamp 35, which is clearly shown in Fig. 3, and engages the edge of the bucket, and said clamp forms 100 an integral part of the arm 36, which is secured by fastenings 37, to the table or platform.

From the foregoing description, taken in connection with the drawings, the operation 105 of my machine will be readily understood, and it is evident that rotation of the operating shaft simultaneously operates the shaft of the freezer and the dasher of the churn, and thus enables the machine to 110

jointly perform the functions of churning and freezing, and also the machine can be used either as a churn or a freezer, as circumstances dictate.

5 To the cross-head, by means of a socket 38 therein is applied the handle 39 of a fan or like device 40, which serves to keep flies or insects away from the machine, or to serve as a cooling medium for the operator.

10 I have shown my mechanism in connection with a churn and ice cream freezer, which are the two most important uses to which my invention could be applied, but I would have it understood that I reserve the

15 right to use my mechanism in connection with any device which it would operate in a practical and desirable manner. The motor could be used for driving a grindstone, for operating a meat chopper and if

20 desired, an implement for cutting cabbage for making kraut could be attached to the reciprocating head in the same manner as the dasher rod, and the action of the head would operate the cutter for cutting the cabbage or in fact any vegetable or material and would prove thoroughly efficient.

I have shown the churn body and ice cream freezer in full lines in position upon the ground, but if desired the freezer may 30 be supported upon the frame and driven by the chain and sprocket connection, as shown in dotted lines, and the mechanism may be

driven by suitable power from the driving pulley 27', as shown in dotted lines, and thus enable the machine to be driven either 35 by hand or power as circumstances require.

The machine, taken as a whole, is calculated to be very useful and desirable upon the farm or in the household and its many uses will be readily understood and appreciated by all skilled in such matters. 40

The arm 35 with its clamp 36 serves the double purpose of holding the freezer rigid as well as keeping the driving sprocket chain 33', taut, which is of great importance 45 in the proper operation of the machine.

I claim:

The combination with a supporting frame for driving mechanism, an arm secured to said frame, a bucket, a clamp carried by the 50 arm for engaging the edge of the bucket, a dasher shaft on the bucket carrying a sprocket wheel, a driving shaft supported on the frame, a sprocket wheel on said shaft, and a sprocket chain passing over the 55 sprocket wheels on the driving and dasher shafts.

In testimony whereof I affix my signature in presence of two witnesses.

JOHN B. KELLY.
